UNITED STATES PATENT OFFICE.

HUGO ERDMANN, OF CHARLOTTENBURG, GERMANY.

METHOD OF REFILLING AERIAL VEHICLES DURING A FLIGHT.

1,035,560.

Specification of Letters Patent. Patented Aug. 13, 1912.

Application filed January 24, 1910. Serial No. 539,842.

To all whom it may concern:

Be it known that I, HUGO ERDMANN, a subject of the German Emperor, and resident at Charlottenburg, Germany, have invented certain new and useful Improvements in Methods of Refilling Aerial Vehicles During a Flight, of which the following is a specification.

The present invention relates to improvements in aerial vessels of that type or class which employ inflatable balloon-like supporting devices and the object of the invention is to provide means by which a body of liquefied gas may be transported in such a vessel and adapted to furnish gas to the inflatable supporting devices as it may be required.

Particularly the invention provides means by which a body of liquefied hydrogen may be conveniently and safely carried by such a vessel and the gas obtained by the vaporization thereof admitted to the balloon as desired.

Heretofore liquefied hydrogen has not been employed for the purpose stated because there were not known means by which it could be conveniently transported. The advantages obtained by being able to use this material will be readily appreciated. A kilogram of liquefied hydrogen will produce eleven cubic meters of hydrogen gas which is sufficient to support a load of fourteen kilograms weight. Therefore it will be seen that in a vessel adapted to transport such material the load bearing capacity can be greatly increased as the liquid returns to gaseous form.

Referring to the accompanying drawing, which illustrates, more or less diagrammatically, an embodiment of the invention, a car or body of an aerial vessel. This car is as usual suspended by suitable ropes from a ring-like frame *b* supported by an inflatable bag *i*. Suitably supported near the frame *b* is a container for liquid hydrogen comprising two concentric holders or receptacles *e*, *e*. These bag-like receptacles are formed of the same material as the supporting balloon *i* and the space separating them is filled with a suitable light weight material adapted to serve as heat insulation for the inner liquid receptacle *e*. Eider-down is particularly adapted for thus filling the space *d* separating the inner receptacle in which liquefied hydrogen *f* is placed from the outer casing *e*. A con-

duit *h* having a valve *g* therein leads from the interior liquid receptacle *e* to the balloon *i* and a branch *k* connects said conduit with the space *d*.

If desired the inner receptacle may be provided with a lining *m* of material, such as cotton adapted to absorb liquefied hydrogen, and the capacity of said receptacle is such that a sufficient quantity of liquefied hydrogen can be carried to replace the gas escaping from the balloon *i* during a long flight. For example, for a balloon having a capacity of 500 cubic meters the receptacle *e* would be of sufficient size to receive about 100 liters of liquefied hydrogen having a weight of approximately 7 kilograms.

Whenever it is desired to increase the lifting capacity of or materially replenish the gas in the balloon *i* the valve *g* is opened when rapid gasification of the liquid body *f* will occur. The space *d* surrounding the receptacle *e* being in constant communication with the conduit *h* may receive a portion of the gas thus delivered through the conduit *h* and the conduit *k* provides for permitting such gas as may accumulate therein and any heated air within said space to pass to the balloon *i* so that the inner receptacle *e* is effectually insulated from heat and its contents can be maintained in liquid condition for a long period of time.

If it is desired to supply gas from the receptacle *e* more rapidly than is possible by manipulation of the valve *g* alone a current of air may be caused to pass through the space *d* about the receptacle *e* by opening suitable inlet and outlet valves *q*, *r*. The passage of air through the body of insulation material in the space *d* will raise the temperature of the liquefied hydrogen and thus increase the rapidity of the gasification thereof.

Having thus described the invention what is claimed and desired to be secured by Letters Patent is:

1. The combination with an aerial vessel including an inflatable bag, of a receptacle for liquefied gas, a valved conduit connecting said receptacle with the inflatable bag, and a casing for said receptacle adapted to protect the contents thereof from the effect of heat and to receive gas generated by the vaporization of the contents of the receptacle, said casing being in constant communication with the inflatable bag.

2. The combination with an aerial vessel

including an inflatable bag, of a receptacle for liquefied gas, a conduit connecting said receptacle with the interior of the inflatable bag, an insulation casing surrounding said 5 receptacle, and a branch conduit connecting the aforesaid conduit with the interior of said casing.

In testimony whereof I have signed my name to this specification in the presence of two subscribing witnesses.

HUGO ERDMANN.
